UNITED STATES PATENT OFFICE

156,338

SET OF PUZZLE CUBES

Wynn Holcomb, New York, N. Y.

Application May 23, 1947, Serial No. 139,245

Term of patent 3½ years

(Cl. D34—15)

To all whom it may concern:

Be it known that I, Wynn Holcomb, a citizen of the United States and resident of the city of New York, Borough of Manhattan, county and State of New York, have invented a new, original, and ornamental Design for a Set of Puzzle Cubes, of which the following is a specification, reference being had to the accompanying drawings, forming part thereof.

In said drawings,

Fig. 1 is a top plan view of a set of puzzle cubes, showing my new design, arranged adjacent to one another, and illustrating a picture;

Fig. 2 is an end view of the arrangement shown in Fig. 1 as seen in the direction of arrow 2;

Fig. 3 is a top plan view similar to Fig. 1 but showing a second surface of each of the cubes, arranged adjacent to one another, and illustrating a second picture;

Fig. 4 is an end view of the arrangement shown in Fig. 3 as seen in the direction of arrow 4;

Fig. 5 is a top plan view similar to Fig. 1 but showing a third surface of each of the cubes, arranged adjacent to one another, and illustrating a third picture;

Fig. 6 is an end view of the arrangement shown in Fig. 5 as seen in the direction of arrow 6;

Fig. 7 is a top plan view similar to Fig. 1 but showing a fourth surface of each of the cubes, arranged adjacent to one another, and illustrating a fourth picture;

Fig. 8 is an end view of the arrangement shown in Fig. 7 as seen in the direction of the arrow 8;

Fig. 9 is a top plan view similar to Fig. 1 but

showing a fifth surface of each of the cubes, arranged adjacent to one another, and illustrating a fifth picture;

Fig. 10 is an end view of the arrangement shown in Fig. 9 as seen in the direction of the arrow 10;

Fig. 11 is a top plan view similar to Fig. 1 but showing a sixth surface of each of the cubes, arranged adjacent to one another, and illustrating a sixth picture;

Fig. 12 is an end view of the arrangement shown in Fig. 11 as seen in the direction of the arrow 12.

In these views the cubes are shown spaced from each other to illustrate that they are separate cubic elements.

I claim:

The ornamental design for a set of puzzle cubes, substantially as shown and described.

WYNN HOLCOMB.
